UNITED STATES PATENT OFFICE.

FRANK H. MORSE, OF PITTSBURGH, PENNSYLVANIA.

DESIGN FOR AN AUTOMOBILE-BODY.

45,948.

Specification for Design.

Patented June 16, 1914.

Application filed April 18, 1914. Serial No. 832,976. Term of patent 7 years.

To all whom it may concern:

Be it known that I, FRANK H. MORSE, a citizen of the United States, residing at Pittsburgh, in the county of Allegheny and State of Pennsylvania, have invented a new, original, and ornamental Design for an Automobile-Body, of which the following is a specification, reference being had to the accompanying drawing, forming part thereof.

Figure 1 is a perspective view; Fig. 2 is a side elevation; Fig. 3 is a front end elevation; and Fig. 4 is a plan view.

I claim:

The ornamental design for an automobile body as shown.

FRANK H. MORSE.

Witnesses:

ELBERT L. HYDE,
AMELIA P. MORSE.
